UNITED STATES PATENT OFFICE.

WILLIAM C. MARCHANT, OF CHICAGO, ILLINOIS.

SWITCHBOARD.

No. 823,183.

Specification of Letters Patent.

Patented June 12, 1906.

Application filed August 7, 1905. Serial No. 273,019.

To all whom it may concern:

Be it known that I, WILLIAM C. MARCHANT, a citizen of the United States, residing at 117 Beach avenue, Chicago, in the county of 5 Cook and State of Illinois, have invented a new and useful Improvement in Switchboards, of which the following is a specification.

My invention relates particularly to means 10 for connecting electric conductors with switches; and my primary object is to provide means for readily effecting safe connections of this character.

My invention is illustrated in its preferred 15 embodiment in the accompanying drawings, in which—

Figure 1 represents a sectional view of a switchboard equipped with my improvement, and Fig. 2 a plan view of the same.

20 In the construction shown, A represents a slab of marble or slate or the like; B, a switch-supporting block of conducting material having joined thereto by a pivot b a switch-blade B'; C, a connecting member 25 serving to join a conductor C' with the block B; D, a block or contact member equipped with a spring-clip D' for the switch-blade, and E a connecting member for joining a conductor (not shown) with the block D.

30 The block B, the member C, and the base-plate A are provided with registering perforations, which receive bolts c, the rear ends of which are effectively housed in countersinks c' at the rear or back portion of the 35 base-plate. The member C is equipped with a rearwardly or downwardly extending socket c'', which is loosely received by registering perforations c''' in the block B and the base-plate A. The socket c'' is provided 40 with a bore receiving the end of the conductor C', the latter being soldered in place. The socket c'' extends only partially through the base-plate, so that it will be observed that the conductor C' and the bolts c are effectively insulated from each other, except 45 through the member C at the front of the base-plate.

The construction at the other end of the switch—namely, at the block D—is the same 50 as that already described, so that it will be

unnecessary to describe the same again in detail.

It will be understood that the connection between the block B, for instance, and the conductor C', for instance, may be made by 55 removing the member C and drawing the conductor through the opening in which the socket c'' is entered, effecting a solder joint between the socket and the conductor, and then replacing the member C. In the same 60 manner a joint may be effected at the member E. The result of the construction is to remove all unsightly connections and also to maintain perfect insulation.

The foregoing detailed description has 65 been given for clearness of understanding only.

What I regard as new, and desire to secure by Letters Patent, is—

1. The combination with a base-plate and 70 a switch-block having registering perforations, of a member located in front of the base-plate equipped with a wire socket housed within and withdrawable from the perforation of the base-plate, and connections between said member and the switch-block, for the purpose set forth.

2. The combination with a base-plate and 80 a switch-block having bolt-receiving perforations and socket-receiving perforations, the bolt-receiving perforations being countersunk in the base-plate, a member having a socket extending through the switch-block and terminating within the base-plate, bolts 85 joining said member with the switch-block and base-plate, and a conductor entered in said socket, for the purpose set forth.

3. The combination of a base-plate, a pair 90 of switch-blocks, one of which is equipped with a pivotal lug, and the other of which is equipped with a spring-clip, a switch pivoted on said pivotal lug and connected with said spring-clip, a base-plate supporting the switch-blocks, each switch-block and the adjacent portion of the base-plate being provided with a socket-receiving perforation 95 and a pair of bolt-receiving perforations, a pair of connecting members having sockets extending through the switch-block and into the base-plate, and bolts connecting said 100

members with the switch-block and the base-plate, substantially as and for the purpose set forth.

4. The combination of a switch-block provided with a socket-receiving perforation and a member bolted thereto having a rearwardly-extending socket extending into said

perforation and provided with a bore for receiving a conductor, for the purpose set forth.

WILLIAM C. MARCHANT.

In presence of—
L. HEISLAR,
J. H. LANDES.
